CONSTRUCTION OF FLOORS, WALLS, ETC.

Herbert Gordon Jenkinson, Adelaide, South Australia, Australia

Application April 30, 1931, Serial No. 534,072
In Australia February 5, 1931

15 Claims. (Cl. 72—70)

This invention relates to the design and construction of a supporting frame for structures subject to loading or pressure such as floors of buildings or other structures, walls of bins and tanks, sides and decks of ships and the like, and in particular it comprises a construction of comparatively light members so mutually interactive and intersupporting that the necessity for using large beams or girders (i. e. main and secondary and other beams) to support such structure is obviated or minimized, thereby reducing the amount of material required to be used.

A frame constructed according to this invention comprises groups of interacting members capable of withstanding flexure and shear of comparatively small section of steel, iron, wood or other material so positioned and securely fastened together that the said members tend to assist each other in two or more directions and by mutual interaction transmit the load or pressure on the structure to the supporting columns, walls, wall beams or struts (as the case may be) generally without the intervention of other members such as main or secondary girders, an adequate number of the said members of comparatively small section being fixed and/or constrained at and/or adjacent to the top or head of the column, strut, wall, wall beam or other support so as to develop considerable negative bending moments in such fixed or constrained members.

Where members of comparatively small section of metal or wood have been used formerly the load has been transmitted by them to large beams or girders which in turn have transferred the load to the columns, struts, wall or the like, but in my invention by the fixture and/or constraint of some of the members at and/or adjacent to supports, struts or the like as above mentioned and the development of great negative bending moment in such members thereby, such large beams or girders are rendered unnecessary except in special cases and the total weight of timber or metal used is therefore minimized by the more effective use thereof.

The following are some ways in which the above-mentioned fixture or constraint may be obtained—

Fixture.—Selected members can be welded or riveted to a seating at the top of the column, strut, wall beam or other support. The seating for the selected members may be a plain plate secured upon the top of a column, or two or more short lengths of girder or channel section secured upon the top or side of a column, or

a length of beam or plate secured upon the top of a wall or other suitable rigid support may be used.

Constraint.—(a) Adjacent to the top of the column or other support all members by reason of being securely fastened together and the mutual interaction due to this fastening are so circumstanced as to develop negative bending moment under load, provided at least one member passing over the column is held firmly where it passes over the column or other support.

(b) Members passing over head of column or support and being firmly held down by weight of a column or the like above them would be a case of constraint.

(c) Members passing over the head of an interior column or other support or passing adjacent thereto would in the case of a uniform load (such as the load on the floor of an elevated water tank of uniform depth) be placed in negative bending moment by such uniform load and, as the load would be equally balanced by its uniformity around the column, the members in negative bending would be constrained by such condition even though none of them might be actually fixed to the column or support.

In order that my invention may be more clearly understood I will describe the same with reference to the accompanying drawings in which:—

Fig. 1 represents a frame for a floor structure or for the deck of a ship supported on columns and consisting of two systems of interacting members, the members of the one system running in one direction and resting upon the members of the other system running in another direction approximately at right angles to the first system.

Fig. 2 is an enlarged view of portion of the frame shown in Fig. 1 for the purpose of showing more clearly the arrangement of the interacting members over the head of a supporting column.

Fig. 3 represents an arrangement of members similar to the arrangement shown in Fig. 1 except that the members of the two systems are placed diagonally in relation to the position of the columns or supports.

Fig. 4 is a similar view to that in Fig. 2 but consisting of members grouped in four superimposed planes.

Fig. 5 is a cross section on line 5, 5 of Fig. 6. 105

Fig. 6 is a plan view partly in section of a frame for a floor or a like structure constructed according to my invention using the arrangement of members shown in Figs. 1 and 2.

Fig. 7 is a side elevation partly in section of 110

portion of the frame for a wall of a bin or tank or side of a ship or the like showing an arrangement of members similar to that shown in Fig. 1.

Fig. 8 is a cross section on line 8, 8 of Fig. 7.

Fig. 9 is a view showing a similar arrangement of members to that shown in Fig. 1 but showing also stiffening members arranged around an opening in a floor and showing also the edge of the floor, tank or other construction resting upon a wall beam.

As shown in Figs. 1 and 2 the frame comprises a system of approximately parallel members 1 of comparatively small cross section running in one direction and resting on a similar system of members 2 running in another direction, preferably approximately at right angles to the direction of members 1, the members 1 being rigidly welded, riveted or otherwise fastened to the members 2 either at all or at a suitable number of points of crossing, the members throughout the structure being suitably spaced and designed to take the stresses due to the loads on the completed floor structure or the like, and a suitable number of members being constrained or securely fixed at or adjacent to the tops of the columns or supports 3, and a suitable number of these constrained or fixed members having a bearing on each support 3 to properly transmit the load thereto. Normally the members 1 and 2 will extend to the full length and width of the floor or other structure but at and adjacent to the columns or other supports shorter intermediate members 4 may be interposed in both systems 1 and 2, and generally shorter lengths may be interposed anywhere in any construction based on my invention to provide for local stresses or strains. In the drawing I have shown the frame carried upon the tops of the columns, but the columns may pass through the floor and the frame be carried by brackets or supports fastened to the side of the column.

According to the construction shown in Fig. 3 the arrangement of members 1, 2 and 4 is in every respect similar to the arrangement shown in Figs. 1 and 2 except that the members 1, 2 and 4 run in a diagonal direction in relation to the position of the columns or supports. Generally in a structure designed and constructed according to my invention it is not essential to have the members 1, 2 and 4 running in any particular direction in relation to the positions of the columns or supports so long as the members are arranged in two systems of interacting members fastened together at some or all of their points of crossing.

According to the modification shown in Fig. 4 the interacting systems of members are arranged as described in Figs. 1 and 2 but grouped in four planes. According to my invention the members can be grouped in any number of planes provided that the members are firmly fastened together at a sufficient number of points of crossing to enable the structure as a whole to resist positive and negative bending moment in two directions, approximately at right angles, and sufficient members are constrained at or near the columns or other supports to carry out the basic idea of my invention.

In Figs. 5 and 6 I have shown portion of a floor or the like embodying my invention using the arrangement of interacting members shown in Fig. 1, but any arrangement of members satisfying the basis of my invention may be used. 1 and 2 are interacting members as described with reference to Fig. 1. A surfacing 5 of metal plating or other suitable material is welded or otherwise fixed to the upper members 1 and fireproof surfacing 6 of gypsum tile, aerocrete, reinforced concrete or

other suitable material is attached to the lower members 2. In the case of inclined or vertical structures according to my invention any necessary surfacing or fireproofing would be fixed to members on either side or on both sides of the frame as desired.

In Figs. 7 and 8 I have shown portion of wall of a bin or tank or side of a ship or the like designed and constructed according to my invention using an arrangement of interacting members similar to that shown in Fig. 1. Members 1, 2 and 4 perform similar functions to the like members in Fig. 1 transferring the load generally without intervention of main or secondary beams or the like to the heads 7 of struts or other supports 8. Surfacing 5 consisting of metal plating or any other suitable material may be attached to either side or both sides of the frame and fireproof surfacing as shown in Figs. 5 and 6 may be attached to either side or both sides of the frame.

As applied to the wall of a tank or the side of a ship the members would be arranged in two systems rigidly fastened together at their points of crossing as above described, some of the members being constrained or fixed at or adjacent to struts or the like joining two opposite sides or joining sides to the bottom or otherwise supported.

In Fig. 9 I have shown on the left hand side an opening in a frame for a floor or similar structure designed and constructed according to my invention, the interacting members 1, 2 and 4 being arranged as represented in Fig. 1. Around the opening the members 1, 2 and 4 are rigidly attached as necessary to the stiffening members 4.

On the right hand side I have shown the edge of the frame for the floor, deck or other construction according to my invention resting on a wall-beam 9 and a suitable number of members 1 rigidly attached to the wall-beam 9 to develop the necessary negative moments to enable the structure to function in accordance with the basic idea of my invention.

Generally a frame designed and constructed according to my invention may be supported on a beam anywhere for some special purpose such as the support of an exceptionally heavy concentrated load. In such case a suitable number of the members which rest on such beam must be fixed or constrained at their place of support on the beam, and also generally the supports of a frame designed and constructed according to my invention need not be regularly arranged but can occur anywhere. Although in the drawings the arrangement of members is generally represented as shown in Fig. 1 the members may be arranged according to the modifications shown in Fig. 3 or in any other way provided that the members are so fastened together and so constrained at or near the supports as to develop positive and negative moments in the structure as a whole in two directions approximately at right angles and to transfer the load on the structure to the supports generally without the intervention of main, secondary or other beams.

It is apparent from the foregoing description that the framework comprises a double-deck arrangement mainly of relatively long members, spaced apart and interspersed with relatively short members placed in alternation but situated only at points of load concentration. The various members in the two decks lie in different directions and are secured together to compose a self-sustaining openwork mat.

In erecting a frame according to my invention the members are held in place by struts or props.

or staging or the like, preferably of timber, until they are fixed. Although it is preferable to fasten the members at all points of crossing they may in some cases be fastened at alternate or even fewer points of crossing. Normally the members of both upper and lower systems or inner and outer systems, as the case may be, extend to the full length and width of the floor or other structure, but at and adjacent to the columns or other supports shorter intermediate members may be interposed in both upper and lower systems or inner and outer systems, as the case may be, and generally shorter lengths may be interposed anywhere in a construction based on my invention to provide for local stresses or strains. The members may be constructed each of a single piece of material or of two or more pieces joined together, the joints being designed and suitable for taking the bending moment and shear at the place where the joint is made.

It will be seen from the foregoing that when members are arranged in two groups so that the members of the one group are approximately at right angles to the members of the other group and are rigidly interconnected therewith, and further that when the members are constrained at the supports, then in such case such frame has no members which by themselves transmit load to the supports, and more important still it needs no such members or main or secondary beams. All load is transmitted through numerous interacting members from the point of application to the supports as can be readily seen when a concentrated load acting on a member of one of the groups is considered. Such a load causes deflection in the member on either side of the point of loading, but as the members of the other group are rigidly interconnected with this loaded member any deflection of it will be resisted by them. They however in turn are rigidly interconnected with the members of the first group and deflection of the members of the second group is resisted by the members of the first group so that a frame is produced in which all the members interact and bending moments are thus generated by any member about other members.

Thus the considered load is not transferred to the supports through any one or two members but is transmitted out in a multiplicity of directions and is transmitted toward the supports through a multiplicity of members. Similarly the load is collected at the supports from a multiplicity of directions and by a multiplicity of members, due to the negative bending moments introduced in the members by their constraint at these points.

What I claim is:—

1. An openwork frame for a floor, or similar structure such as a wall of a bin or tank or side or deck of a ship, consisting of two systems of intersecting members the interstices of which are adapted to remain unfilled, the members of the one system running in one direction and resting upon the members of the other system running in another direction approximately at right angles to the first system, and the members of the one system being rigidly secured to the members of the other system at certain of their intersections.

2. An openwork frame for a floor or deck of a ship or similar structure adapted to be supported on columns or other supports, comprising an upper system of approximately parallel members of comparatively small cross section running in one direction, a similar lower system of members

right angles to the upper members, and means by which the members of the upper system are rigidly secured to the members of the lower system at certain of their intersections, the interstices of the resulting framework being adapted to remain open, a suitable number of the lower or upper members having a fixed bearing on each support to properly transmit load thereto and develop negative bending moment.

3. For transmitting load to a support, a frame comprising two associated groups of members capable of resisting flexural stress and shear, the members of the one group being superimposed upon and extending transversely with respect to the members of the other group, the members of both groups being rigidly interconnected to mutually interact to develop bending moments about each other so that a load applied at any point is transmitted in a multiplicity of directions, the frame being constrained at the support so that the members develop negative bending moments about the support and concentrate load from a multiplicity of directions to such support.

4. For transmitting load to a support, a frame as set forth in claim 3 characterized by additional short members at points of heavy stress, the short members being similarly arranged in two groups and rigidly interconnected with each other and with the two main groups.

5. For transmitting load to a support, a frame as set forth in claim 3 characterized by additional short members at the support, the additional short members being similarly arranged in two groups and interconnected with each other and with the two main groups and being constrained at the support.

6. A frame for transmitting a load from a surface to supports characterized by two associated groups of substantially similar members capable of resisting flexural stress and shear, the members of the one group being superimposed upon and extending transversely with respect to the members of the other group and being substantially similarly arranged, the members of both groups being rigidly interconnected to mutually interact to develop bending moments about each other, and the frame being constrained at the supports so that the members develop negative bending moments about the supports.

7. In a frame as set forth in claim 6 additional shorter members for each group each rigidly interconnected with the members of its group, such members being in parallel alignment with and in the same plane as the other members of its group and arranged about the points of maximum bending moment.

8. A frame for transmitting a load from a surface to supports characterized by associated groups of substantially similar members capable of resisting flexural stress and shear, the members of alternate groups being superimposed upon and extending transversely with respect to the members of the remaining groups, all groups being similarly arranged, the members of all the groups being rigidly interconnected to mutually interact to develop negative bending moments about each other and the frame being constrained at the supports so that the members develop negative bending moments about the supports.

9. In a frame as set forth in claim 8, additional shorter members for each group each rigidly interconnected with the members of its group, such members being in parallel alignment with and in the same plane as the other members of running in another direction approximately at

its group and arranged about the points of maximum bending moment.

10. For transmitting load from a surface to a support, a frame comprising a group of substantially parallel members capable of resisting flexural and shear stress, certain of said members being arranged to bear on said support, another group of flexural and shear resisting members superimposed upon said first group, the members 10 of the second group being similar in shape and similarly arranged to the members of the first group but extending transversely thereof, the two groups being rigidly connected together at their 15 points of crossing so that the members develop bending moments about each other and negative bending moments about the support.

11. For transmitting load from a surface to a support, a frame comprising a group of members capable of resisting flexural and shear stress, certain of said members being rigidly secured to said support, another group of flexural and shear resisting members superimposed upon said first group, the members of the second group being similar in shape and similarly arranged to the members of the first group but extending transversely thereof, the two groups being rigidly connected together at certain of their points of crossing so that the members develop bending moments about each other and negative bending 30 moments about the support.

12. For transmitting a distributed load to supports, a frame comprising two associated groups of substantially similar members capable of resisting flexural stress and shear, the members of the one group being superimposed upon and extending transversely with respect to the members of the other group and being substantially similarly arranged, the members of both groups being rigidly interconnected to mutually interact 40 to develop bending moments about each other, the frame being constrained at the supports so that the members develop negative bending moments

about the supports, and the frame having upon it a covering of sheet material.

13. For transmitting load to a support, a frame having no main beams but consisting essentially of two associated groups of substantially similar members which are capable of resisting flexural stress and shear and are not embedded in a stressed medium, the members of the one group being superimposed upon and extending transversely with respect to the members of the other group, and the members of the one group being rigidly secured to the members of the other group at certain of their points of crossing to develop bending moments about each other and being constrained at the support to develop negative bending moments about the support.

14. For transmitting load to a support, a frame having no main beams but consisting essentially of two associated groups of members capable of resisting flexural stress and shear, the members being of relatively small cross-section and not embedded in a stressed medium, the members of one group being superimposed upon and extending transversely of the members of the other group, and the two groups of members being rigidly connected together at certain of their points of crossing to develop bending moments about each other and being constrained at the support to develop negative bending moments about the support.

15. In a building construction, a framework consisting of a double deck of relatively long spaced members, the members in one deck lying in different directions from the members in the other deck, relatively short members included in each deck being placed in alternation with the respective long members and situated at points of load concentration, and means to secure the various members of the two decks together to compose a self-sustaining, openwork mat.
